UNITED STATES PATENT OFFICE.

JOHN A. GROVE, OF BLUFFTON, INDIANA.

FENCE.

SPECIFICATION forming part of Letters Patent No. 298,575, dated February 12, 1884.

Application filed July 14, 1883. (No model.)

To all whom it may concern:

Be it known that I, JOHN A. GROVE, a citizen of the United States, residing at Bluffton, in the county of Wells and State of Indiana, 5 have invented certain new and useful Improvements in Fences; and I do declare the following to be a full, clear, and exact description of the invention, such as will enable others skilled in the art to which it appertains to make and 10 use the same, reference being had to the accompanying drawings, and to the letters and figures of reference marked thereon, which form a part of this specification.

My invention relates to improvements in 15 fences; and it consists in the construction, combination, and arrangement hereinafter described and claimed.

In the drawings, Figure 1 is a side view of 20 my fence. Fig. 2 is a vertical section thereof, with one of the stakes broken away to show the upper end of the post. Fig. 3 shows detail views of the fastening between stakes and 25 riders. Figs. 4 and 5 show the fastening between the post and the rails, and Fig. 6 shows a manner of fastening post and rails different from that illustrated in the other figures.

My fence is composed of the posts A, the stakes B B', the rails C, the riders D, the loops E, and the fastening-wires F G, all of which 30 will be described. The posts A are set in the ground a suitable distance apart and in a straight line, no worm being given. The upper end of these posts, on the side next the rails—which side I call, for convenience of reference, the "back" of the post—is beveled in a plane parallel with the incline of the stake B', and the said stake is rested thereagainst in building the fence, as shown in Fig. 2. I call the side of the post opposite the rails its "face."

40 The rails C are arranged with the ends of the contiguous ones in the adjacent panels, one above the other, alongside the posts, and they are secured thereto by the wire F, which is bent, as shown, to provide two loops, f f', one 45 of which is passed tightly around the post alone, and the other is carried around the post and rails. By means of the loop f around the post the rails, which are secured thereto by the loop f', are prevented from any vertical 50 displacement or movement, which is common where but a single loop is employed.

It will be readily seen that the loop f might be arranged below or between the rails; but I prefer to arrange it above the same, as shown, in which arrangement I start with the wire at 55 a point on the face of the post at the right edge, in line with the lower side of the under rail, and carry it diagonally across the face thereof to the opposite or left edge, in line with the upper edge of the top rail. The loop 60 f is then carried around the post, and the wire passed under the bend between the diagonal portion and the loop f, carried back along the top of the upper rail, and down along the back of the rails in a diagonal line, as shown in Fig. 65 5, to a point in line with the starting-point, to which the wire is brought, and its two ends twisted or otherwise suitably fastened. By this arrangement the loop f is brought above the rails, which is the most convenient point 70 to form it, and whereby I find in practice a stronger and better fastening is had. The use of both loops is desirable, as it will be seen that the rails secured thereby cannot slip unless both loops slip simultaneously. The strain 75 on the said loops being unequal, this slipping cannot occur; hence a rigid, secure fastening of the rail is provided without the use of nails or spikes, as is common. The stakes have their 80 lower ends set into or on top of the ground, and their upper ends are crossed above the posts, forming a saddle to receive the riders. The stake B' is rested against the beveled upper edge of the post, and the stake B rests alongside the said post, as shown. In order 85 to clamp the stakes firmly in position on the post, I employ the wire loop E, which is passed around the stakes and post at a point below the upper row of rails. This loop is twisted tight, and bears, as will be seen, on the right 90 side of the post, and holds the same close against the side of the stake B and clamps its beveled edge against the bearing-face of the stake B', whereby the said post is held firmly in its position, and the stakes are also prevented from displacement, as will be readily 95 understood. This tie may be adjusted up or down, in order to permit the lower ends of the stake to be moved away from or toward the posts, enabling a neat regular setting of the 100 fence, either on a level or hillside, as will be readily understood. The riders D are seated

in the saddles formed by the crossed ends of the stakes B B', with the ends of the adjacent riders lapped one above the other, as shown. I then bind the riders and stakes with the wire 5 G. I start this wire on the face of the stake B', and pass it between the two riders, thence around the stake B, up over the top rider, over and down between the two riders, around back of the under rider, and thence forward to the starting-point; when the ends of the wire are twisted or otherwise suitably fastened together. By this arrangement I clamp the two riders 15 together and to the stakes, thereby preventing their being drawn longitudinally apart or lifted vertically from the saddle formed by the stakes.

In Fig. 6 I show an arrangement of posts, rails, and wire, whereby the latter is used in a single strand. Where so desired, this could 20 be made continuous, with the fastening G between the riders and stakes, the wire from the post and rails being extended up to the saddle, and its upper end utilized to form the loop

G, twisted, as before described. I prefer, however, the construction shown in Figs. 1, 2, and 25 4 and hereinbefore clearly set forth.

Having thus described my invention, what I claim, and desire to secure by Letters Patent, is—

The fence hereinbefore described, consisting of the single posts having their upper ends beveled and extended above the top rails of the panels, the rails C, having their ends lapped one upon the other and upon the posts A, the double-loop wire fastenings F, the stakes B, 35 the stakes B', rested upon the beveled upper end of the posts A, the riders D, bound to the stakes by the wires G, and the adjustable loops E, passed around the stakes and between two adjacent rails, as and for the purposes set forth. 40

In testimony whereof I affix my signature in presence of two witnesses.

JOHN A. GROVE.
